Des. 233,504

Patented Nov. 5, 1974

233,504

STILE CLAMP

William C. Wildman, 3915 Hoover St.,
Boise, Idaho 83705

Filed Dec. 26, 1972, Ser. No. 318,080

Term of patent 14 years

Int. Cl. D8—05

U.S. Cl. D8—72

FIG. 1

FIG. 2

FIG. 1 is a top perspective view of a stile clamp embodying my new design, with the clamping jaws in the rearwardmost position.

FIG. 2 is a top plan view with the clamping jaws in the forwardmost position.

I claim:

The ornamental design for a stile clamp, substantially as shown and described.
